CLAIM

The ornamental design for a protective case for display device, as shown and described.

DESCRIPTION

FIG. 1 is a top, front, right side perspective view of a protective case for display device showing our new design; FIG. 2 is a top, rear, left side perspective view thereof; FIG. 3 is a front view thereof; FIG. 4 is a rear view thereof; FIG. 5 is a top view thereof; FIG. 6 is a bottom view thereof; FIG. 7 is a right side view thereof; FIG. 8 is a left side view thereof; and, FIG. 9 is an enlarged view of detail 9 in FIG. 1.

Dash-dash broken lines illustrate portions of the protective case for display device that form no part of the claimed design. Dash-dot broken lines shown on the protective case for display device in FIGS. 1-8 depict a symbolic break in length and form no part of the claimed design.

1 Claim, 7 Drawing Sheets
